UNITED STATES PATENT OFFICE.

HARRY PRINCE, OF BUFFALO, NEW YORK, ASSIGNOR TO THE AMERICAN MINE DOOR COMPANY, OF CANTON, OHIO.

CABLE SPLICE.

Application filed January 13, 1923. Serial No. 612,560.

To all whom it may concern:

Be it known that I, HARRY PRINCE, a subject of the King of Great Britain, residing at 283 14th Street, Buffalo, in the county of Erie and State of New York, have invented a new and useful Improvement in Cable Splices, of which the following is a specification.

This invention relates to improvements in cable splices.

The principal object of the invention is to provide a cable splice which is self locked upon the connected cable ends. A further object is to provide a cable splice which is self acting in the development and maintenance of the self locking effect and which has such action incident to its compression upon the cable ends to be connected.

With the above objects in view the invention consists generally in a cable splice of integral formation having yieldable locking extensions and parts with which said extensions co-operate to lock the splice in compressed relation upon, and in secure and effective engagement with, the cable ends. The invention also consists in the combination with said extensions of parts which act upon them to effect and maintain their interlocking engagement in co-operating recesses, thereby to make the cable splice self locked and positively locked in compressed condition and in secure coupling engagement with the adjacent cable ends.

The invention is illustrated in the accompanying drawings, wherein:

Figure 1 is an elevation of the blank which is compressed into annular form to provide the cable splice.

Figure 2 is a perspective view showing the cable splice in the form in which it is offered for sale.

Figures 3 and 4 are elevations taken at different angles showing the cable splice compressed upon the adjacent cable ends.

The cable splice is produced in annular cross section from a blank having the form shown in Figure 1. This blank consists of a flat strip of metal having a transversely centrally located body portion 1 with parallel or substantially parallel sides 2. A centrally located tongue 3 of generally tapering form projects longitudinally from the body portion at one end of the blank and at its other end the blank is provided with a centrally located longitudinal recess

4 of general V-shape in which the tongue 3 is engaged when the splice is compressed. The recess 4 delimits at the sides of the blank a pair of longitudinally extending tapering tongues 5 whose outer sides are formed as straight prolongations of and of continuous extent with the sides 2. The tongues 5 are formed at their extremities with extensions 6 which though integral with said tongues may be flexed upon them laterally in either direction and which are set in converging relation, their side edges extending laterally inward from the adjacent side edges of the tongues 5.

At the end from which the tongue 3 extends the body portion 1 is provided adjacent its sides with recesses 7 which conform in all respects to the extensions 6 and in which said extensions are engaged when the splice is compressed upon the cable ends. The recesses 7 extend in converging relation into the body portion 1 and delimit an intervening web 8 from which the tongue 3 directly projects, the sides 9 of the web extending divergently to the line at which the web and tongue are integrally united whereby laterally raised shoulders 10 are provided, which shoulders may be regarded as located at the sides of the tongue at its base or at the inner sides of the recesses 7 at the openings thereof. The recesses 7 also delimit at the sides of the blank longitudinally extending fingers 11.

The engaging face of the blank may be provided with shallow longitudinal grooves 12 which extend from the bases of the recesses 7 to points along the tongues 5 and aid the secure engagement of the splice upon the cable ends. While these grooves may be preferred out of an abundance of caution, the splice will be effective without them, for which reason their provision is optional.

As offered for sale the splice is fashioned into annular cross section from the flat blank, the tip of the tongue 3 being introduced through the space between the extensions 6 into the mouth of the recess 4 and the diameter of the splice being suitably greater than the diameter of the cable ends to be joined, whereby said cable ends may be readily inserted into the splice at either side thereof.

The splice in the form shown in Figure 2 is compressed or reduced by means of a

suitable instrument upon the adjoining cable ends thereby to couple the same and as so compressed or reduced has secure coupling engagement with and upon said cable ends, 5 the parts of the splice being brought into the relations shown in Figures 3 and 4.

In the compression of the splice the tongue 3 is introduced into the recess 4 until its tip engages in the vertex of said recess. 10 As the tongue 3 is brought into the recess 4 the extensions 6 are in contacting engagement with the inclined sides of said tongue and by said sides are flexed laterally outward upon the tongues 5 until such time as 15 the points of contact of said extensions aline transversely with, that is to say engage upon, the laterally presented shoulders 10 at the base of the tongue 3. Thereafter and during the further movement of the tongue 20 3 into the recess 4 the extensions 6 are introduced into the recesses 7 and by the inclined outer sides of the recesses 7 (which sides are also the inner sides of the fingers 11) are flexed laterally inward upon the 25 tongues 5, whereby when the tongue 3 is completely engaged in the recess 4 the extensions 6 are completely and conformably engaged in the recesses 7. As engaged in the recesses 7 the extensions 6 are directed 30 laterally inward and circumferentially behind the shoulders 10 and are thereby overhung by said shoulders. The engagement of the extensions 6 in the recesses 7 is maintained by the co-operation of the fingers 11 35 which positively prevent any lateral outward movement of said extensions and the inclined sides 9 of the web 8 which oppose and prevent any circumferential outward movement of said extensions. 40 It will thus be apparent that by virtue of the extensions 6 and the parts which co-operate therewith a self locking action of the splice is set up incident to the compression of the splice upon the adjoining cable 45 ends and that this locking action is at all times thereafter positively maintained whereby to insure the permanence of the secure and effective coupling engagement of the splice upon the adjacent cable ends, regardless of any counter forces which may 50 be developed.

A modification within the scope of the invention and the terms of the appended claims may be resorted to, according to 55 which the fingers 11 are eliminated but such a form, although useful and effective, is not as desirable as the form disclosed since the self locked effect secured by the engagement of the extensions 6 against the inclined sides 60 9 and under the shoulders 10 is not self initiated but must first be established by drawing said extensions inward by a suitable instrument nor will said extensions be positively held in their locking positions.

65 It will also be understood that other minor

modifications may also be resorted to without departing from the principles and scope of the invention as defined by the claims.

Having fully described my invention, I claim:

1. As an article of manufacture a cable splice produced or to be produced in annular cross sectional form from a flat blank having a body portion, a central tapering tongue extending longitudinally beyond one end of said body portion, a pair of tongues projecting longitudinally from the other end of said body portion and delimiting between them a V-shaped recess in which said central tongue may be conformably engaged, a laterally flexible terminal extension on each tongue of said pair of tongues, and a web connecting said central tongue and said body portion and having sides which diverge in the direction in which the sides of said central tongue converge, thereby to provide laterally presented shoulders at the base of said central tongue behind which said extensions may be laterally flexed in converging relation and into contact with the sides of said web. 70 80 85 90

2. As an article of manufacture a cable splice produced or to be produced in annular cross sectional form from a flat blank having a body portion, a central tapering tongue extending longitudinally beyond one end of said body portion, a pair of tongues projecting longitudinally from the other end of said body portion and delimiting between them a V-shaped recess in which said central tongue may be conformably engaged, and a laterally flexible terminal extension on each tongue of said pair of tongues, said extensions being in converging relation, the body portion having recesses conforming to said extensions and in which said extensions are engaged, said recesses delimiting between them a web which connects said central tongue and said body portion and has sides which diverge in the direction in which the sides of the tongue converge, thereby to provide laterally presented shoulders at the base of said central tongue and also delimiting at their outer sides longitudinally extending fingers which act upon the extensions as they enter said recesses to flex them laterally behind said shoulders and into contact with the sides of said web. 100 110 115 120

3. As an article of manufacture a cable splice produced or to be produced in annular cross sectional form from a flat blank having a body portion, a central tongue extending longitudinally beyond one end of said body portion, a pair of tongues projecting longitudinally from the other end of said body portion and delimiting between them a recess in which said central tongue may be engaged, a laterally flexible terminal extension on each tongue of said pair 125 130

of tongues, and a web connecting said central tongue and said body portion and being broader where it joins said central tongue than at other points in its extent, 5 thereby to provide laterally presented shoulders at the base of said central tongue behind which said extensions may be laterally flexed into contact with the sides of said web.

10 4. As an article of manufacture a cable splice produced or to be produced in annular cross sectional form from a flat blank having a body portion, laterally presented shoulders located beyond one end of said 15 body portion, and extensions located beyond the other end of said body portion and which may be flexed laterally behind said shoulders, thereby to lock said splice in compressed relation.

20 5. As an article of manufacture a cable splice produced or to be produced in annular cross sectional form from a flat blank having a body portion, laterally presented shoulders located beyond one end of said 25 body portion and extensions located beyond the other end of said body portion, the body portion having recesses adjacent said shoulders in which said extensions are engaged, said recesses delimiting fingers at the 30 sides of the body by which said extensions as

they enter said recesses are flexed laterally behind said shoulders, thereby to lock said splice in compressed relation.

6. The cable splice herein described consisting of a single integral metallic strip 35 bent to form a ring compressible around the strands of a cable, said ring having parallel sides and having a central tapered tongue and a pair of tapered tongues opposed to the central tongue and between 40 which the first-mentioned tongue is snugly received when the ring is compressed around the cable, the last-mentioned tongues each having an inwardly directed terminal extension and there being at the sides of the 45 central tongue inwardly directed notches in which the terminal extensions are snugly received, said notches defining lateral shoulders at the base of the central tongue against 50 which the terminal extensions engage and ride to be flexed outwardly during compression of the ring and there being fingers at the outer sides of the notches to flex the extensions inwardly behind the shoulders whereby to lock the compressed ring against 55 longitudinal and circumferential opening strain.

In testimony whereof I affix my signature.

HARRY PRINCE.
